UNITED STATES PATENT OFFICE

HARRY W. BUNDY, OF DETROIT, MICHIGAN, ASSIGNOR, BY MESNE ASSIGNMENTS, TO
BUNDY TUBING COMPANY, OF DETROIT, MICHIGAN, A CORPORATION OF MICHIGAN

APPARATUS FOR AND METHOD OF MAKING FINNED TUBING

Application filed December 30, 1927. Serial No. 243,512.

This invention relates to an apparatus for and method of making finned tubing.

The invention is concerned particularly with the making of finned tubing wherein a 5 helical fin for heat transferring purposes or the like is wound upon a preformed tube. According to the invention this preformed tube moves lengthwise through the apparatus and at the same time is given a rotational movement. A simplified fin winding apparatus is 10 provided by this invention and also a method is afforded for effecting these mentioned movements of the tube.

In the accompanying drawings:

15 Fig. 1 is a side elevation of the fin applying apparatus, or winding head with some parts cut away and some parts in section, showing a tube in place with the fin stock being wound thereon.

20 Fig. 1a is a view showing a tube wherein the fin is wound thereon in a modified manner.

Fig. 2 is an end view of the winding head looking from the left side of Fig. 1.

25 Figs. 3, 4, and 5 are sectional views taken through the corresponding section lines of Fig. 2, showing the die construction for giving the fin stock an L shape in cross section before being wound on the tube.

30 Fig. 6 is a plan view of the winding head.

Fig. 7 is a perspective view of one of the die members.

Fig. 8 is a perspective view of the complementary die member.

35 Fig. 9 is an enlarged view showing in detail an operation on the fin just prior to its being wound upon the tube.

Fig. 10 is a view partly in section of a further modified type of finned tube.

40 Fig. 11 is a view similar to Fig. 10 showing a further modified type of tube which can be made, wherein no preformed tube is used.

Referring to Fig. 1, a preformed tube of any desired construction is shown at 1, and a 45 spiral fin is shown as consisting of a helical fin 2 rising from a band of metal 3 flatly abutting the tube. Thus it will be seen that the fin stock is L shaped in cross section when it is placed upon the tube.

50 The winding head consists primarily of

driven pressure rolls 5 and 6, the pressure roll 5 being mounted upon a shaft 7, and driven by means of pinions 8 and 8a, there being an interposed thrust bearing at 9. The pressure roll 6 is mounted upon a shaft 10 which carries at its lower end a gear wheel 11. A drive shaft 12 carries the pinion 13 for meshing with the gear wheel 11 and also with the gear wheel 14 which drives the shaft upon which the pinion 8 is mounted. 60

The shaft 10 upon which the pressure roll 6 is mounted is journaled in a bearing block 15 which is adjustable so that the pressure roll 6 can be adjusted toward and away from and angularly with respect to the pressure 65 roll 5. For adjustably mounting this bearing block a plurality of set screws 16 and 17, 18 and 19 may be provided which engage the block on several sides to hold it in position. It will thus be seen that by manipulating 70 these set screws the angular position of the pressure roll 6 and also the distance between this pressure roll and the roll 5 can be varied. This adjustment affects also the gear 11, but the intermeshing teeth with the pinion are 75 loose enough to permit this.

The stock for the finned tube is preferably fed to the winding head in flat strip form and it is run through suitable dies to give it an L shape in cross section just prior to being wound upon the tube. While this is preferable, the stock may be fed to the machine in angular form. However, referring to Fig. 2, the strip stock is fed into the machine at the point carrying the appropriate 80 legend. At this point the stock is engaged by the complementary die members 20 and 21. These die members are fitted together by means of pins 22 which extend through apertures 23 (Figs. 7 and 8). Preferably springs 24 are interposed between the die members, and in order to bring the die members together with operating pressure a pivoted locking device 25 (Fig. 6) is provided. In a 85 position shown in this figure the locking member holds the die together and ready for operation. In order to loosen the dies the locking member is shifted to dotted position and the coil springs force the dies apart. 90 This permits threading and originally setting 95 100

up the machine for operation. As will be seen, referring to Figs. 3, 4, and 5, these die members first place a slight curve in the strip stock and gradually increase this curve until 5 the stock is substantially right angular in cross section. The dotted lines α (Fig. 6) are indicative of the gradual change in shape given to the strip stock.

In the operation of the mechanism as thus 10 far described the pressure rolls 5 and 6 are rotated. The stock having been fed or threaded into these rolls is engaged thereby with the fin portion 2 directly engaged between the pressure rolls. These rolls are 15 brought together with sufficient pressure to pull the fin stock in through the dies so that no other stock feeding mechanism is required. The roll 6 is adjusted so that its fin engaging surface is at an angle to the surfaces of the 20 roll 5, as shown in Figs. 1 and 9. The pressure between these rolls is such as to compress the metal of the fin 2 with the metal near the outer edge of this fin 2 compressed more than it is next the inner edge or close to the 25 tube. Inasmuch as the fin 2 is to be helically wound the diameter at the outer edge of the tube must necessarily be greater than the diameter of its inner edge or where it abuts the tube, and by reason of the compressing 30 of the metal and the thinning down of the fin near its outer edge or rather the thinning down of the fin progressively from its inner to its outer edge this increase of diameter is afforded. In fact the metal is so 35 compressed that the fin is given a curvature by this compressing and preferably the curvature is such that the normal inside diameter of the fin is less than the outside diameter of the tube.

40 Thus as the machine is operated the fin stock moves in under the tube 1 where it is given a curvature by the compressing of the metal of the fin so that this finned stock moves upwardly and around the tube. The 45 fin stock, by reason of having a normal inside diameter less than the outside diameter of the tube, grips the tube very tightly.

At this point description of how the tube is 50 moved longitudinally and rotationally becomes necessary. It will be remembered that the finned stock is given a curvature so that it will grip the tube tightly. It is also forcibly fed by the action of the pressure rolls. Disposed immediately above the pressure 55 rolls and above the tube is what may be termed a lead die 26 (Figs. 1 and 6). This lead die has a slanting surface 27 and it is preferably interchangeable being removably held upon the apparatus by suitable screws 60 28. As perhaps best shown in Fig. 6 the fin stock moves around the tube and the fin portion contacts with the slanting surface 27 of this lead die. Due to the fact that the stock 65 tightly engages the tube, the tube is given a rotational movement as the finned stock is

fed or pushed through pressure rolls on to the tube. At the same time, the fin engages this slanting surface wherein a sort of cam action is set up so that the fin, together with the tube which is gripped tightly thereby, are both 70 moved forwardly. Thus in the continued operation the tube is moved both rotationally and forwardly of the machine by reason of the winding of the finned stock thereon. Also the pitch of the slanting surface of the 75 lead die determines the pitch of the helical fin. As the lead die is interchangeable dies of a varied pitch can be used for effecting different pitched fins. As shown in Fig. 1 the tube engaging portion 3 of the stock is arranged 80 so that adjacent convolutions abut each other and the lead die is designed to give the proper pitch to effect this construction. However, by referring to Fig. 1a, the tube engaging portions are overlapped and to accomplish 85 this all that is necessary is the use of a properly designed lead die to lessen the pitch of the helical fin. As shown in Fig. 10 the pitch of helical fin has been increased so that the several convolutions of fin stock are spaced 90 apart from each other. This can be accomplished by the use of a properly constructed lead die. Of course, it is within the invention to vary the width of the tube engaging band 3 of the stock so as to obtain overlapping 95 without changing the lead die. The varying of the width of the tube engaging band of the fin to obtain various other effects, with or without changing the lead die, is within the invention.

100 It is also possible with the lead here shown to manufacture a tube with overlapped sections but without any preformed tube on the interior. Such as shown in Fig. 11.

After the fin has been applied to the tube, 105 the whole tube may or may not be subjected to a bath of sealing material such as solder. Such a bath effects a tight seal between the tube and fin, but the tube is satisfactory for use without the application of solder.

110 In making the form of tube shown in Fig. 11, the several convolutions are overlapped to form a tubular body. Instead of employing a preformed tube around which the convolutions are coiled, an arbor may be used for the overlapping coils. The use of such arbor, however, is old and generally understood by those in the art, and accordingly is not shown. With a tube of this nature it is preferable to complete and seal the convolutions by solder 115 or other sealing metal to make the same fluid tight.

I claim:

120 1. An apparatus for forming finned tube which comprises, a pair of pressure rolls to which strip stock is guided for forming a fin with the stock engaged between the rolls, the 125 engaging surfaces of the rolls being disposed at an angle to each other whereby to displace the metal and give the strip stock a curvature, 130

means for rotating the rolls so that the rolls also feed the curved fin stock, and means for receiving a member in position to be encircled by the curved fin stock as it comes from the 5 rolls, and means including a cam surface against which the curved fin stock strikes for effecting the helical pitch of the fin.

2. An apparatus for forming finned tube comprising, a pair of pressure rolls to which 10 the strip stock is guided for forming a fin with the stock engaged between the rolls, the engaging surfaces of the rolls being disposed at an angle to each other whereby to displace the metal and give the strip stock curvature, 15 means for rotating the rolls so that the rolls also feed the curved fin stock, and means for receiving a member in position to be encircled by the curved fin stock as it comes from the rolls, and means including a cam surface 20 against which the curved fin stock strikes for effecting the helical pitch of the fin, said means being removably held on the apparatus whereby means for effecting various pitches of the fin stock can be utilized.

3. An apparatus for forming finned tube comprising, a pair of pressure rolls arranged at right angles to each other having engaging surfaces between which is disposed strip stock for forming a fin, one of these rolls 30 being adjustable angularly with respect to the other, whereby the fin engaging surfaces can be angularly disposed to displace the metal of the fin and give the fin a curvature, means for rotating the rolls, and means for 35 positioning a member so that the curved fin, as it is fed from the rolls, encircles the member.

4. In apparatus for forming finned tube comprising, means for receiving a cylindrical 40 member, a pair of pressure rolls one of which rotates on an axis substantially parallel to the length of the said member, and the other of which rotates on an axis substantially at right angles to the length, means for guiding strip stock between the rolls, said rolls engaging the strip stock with sufficient pressure to displace the metal thereof and give the strip stock curvature, and means for rotating the 45 rolls to feed the curved strip stock around the said cylindrical member.

5. An apparatus for forming finned tube comprising, means for receiving a cylindrical member, a pair of pressure rolls one of which 50 rotates on an axis substantially parallel to the length of the said member, and the other of which rotates on an axis substantially at right angles to the length of the tube, means for guiding strip stock between the rolls, said 55 rolls engaging the strip stock with sufficient pressure to displace the metal thereof and give the strip stock curvature, means for rotating the rolls to feed the curved strip stock around the said member, said rolls being adjustable angularly with respect to the other

to vary the relative angle between their stock engaging surfaces, whereby the displacement of the metal and the resulting curvature of the stock can be varied.

6. An apparatus for forming finned tube 70 comprising, means for receiving a cylindrical member, a pair of pressure rolls one of which rotates on an axis substantially parallel to the length of the said member, and the other of which rotates on an axis substantially at right angles to the length of the tube, means for guiding strip stock between the rolls, said rolls engaging the strip stock with sufficient pressure to displace the metal thereof and give the strip stock curvature, means for rotating the rolls to feed the curved strip stock around the said member, the roll operating on an axis perpendicular to the said member being adjustable angularly and toward and away from the cooperating roll whereby to vary the relative angularity of their stock engaging surfaces and accordingly vary the displacement of the metal and the resulting curvature of the fin.

7. An apparatus for applying a helical fin 90 to a preformed tube comprising, dies through which flat strip stock is fed, said dies giving the strip stock an L shape in cross section, a pair of pressure rolls which engage the leg 95 of the L which forms the fin, the engaging surface of these pressure rolls being disposed at an angle to each other so as to compress this leg of the L and give the stock the curvature, means for holding a tube, means for rotating the rolls to feed the stock, said tube being in a position whereby the fin wraps itself around the tube as it is fed from the rolls, and means engaging the fin substantially at the point where it wraps around the tube for giving the fin its helical pitch.

8. The method of winding a helical fin on a preformed tube which comprises, forcibly feeding the fin stock and winding the same stock around the tube with sufficient tightness 100 to effect rotation of the tube.

9. The method of winding a helical fin on a core which comprises, feeding the fin stock, effecting a curvature of the fin stock and then winding the fin stock on the core 110 with sufficient tightness for the stock to grip the core and cause rotation thereof upon the feeding of the stock.

10. The method of winding a helical fin on a preformed tube which comprises, effecting a curvature in flat strip fin stock, forcibly feeding this stock around the tube with the fin stock engaging the tube with sufficient pressure to effect rotation thereof due to the forcible feeding of the fin stock.

11. The method of winding a helical fin on a preformed tube which comprises, loosely supporting the tube, effecting a curvature of flat fin stock so that normal inside diameter 130 is less than the exterior diameter of the tube,

forcibly feeding the fin stock around the tube with the fin stock tightly gripping the tube and effecting rotation thereof due to the forcible feeding of the fin stock.

5 12. The method of applying a helical fin on a preformed tube which comprises, loosely supporting the tube, winding fin stock tightly on the tube, effecting lengthwise movement of the tube by causing rotation of the

10 fin stock and advancing the fin stock by employing its helical formation and screw means, said fin stock holding the tube with sufficient tightness to carry the tube with it.

13. The method of winding a helical fin on 15 a preformed tube which comprises effecting a curvature on strip fin stock, forcibly feeding the stock around a tube, effecting rotation of the tube by reason of forcibly feeding the stock, and effecting lengthwise movement 20 of the tube by utilizing the screw effect obtained from the helical fin.

14. The method of winding a helical fin on a preformed tube which comprises, effecting a curvature to strip fin stock, forcibly feeding this stock around the tube with the stock tightly engaging the tube, effecting rotation of the tube by reason of the forcible feeding of the fin stock, and simultaneously setting the pitch of the helical fin, as it is forcibly 30 fed, and advancing the tube by reason of the fin tightly engaging the same.

15. The method of winding a helical fin around a preformed tube which comprises, effecting a curvature of flat strip stock for 35 forming a fin, forcibly feeding this stock around the tube with the stock tightly engaging the tube, employing die means for giving the fin its helical pitch, and effecting rotational and lengthwise movement of the 40 tube by the forcible feeding of the stock.

16. In the process of making a helical winding for finned tubes or other purposes, the steps of forming successive helical convolutions in stock which comprises force- 45 fully pushing stock, and simultaneously effecting a curvature in the stock by the pushing instrumentality, by flowing the material of the stock, such that successive convolutions of the pushed stock wind themselves 50 into helical form upon an adjacent core.

17. An apparatus for forming a helical winding from strip metal stock, comprising a pair of pressure rollers having opposed faces through which the strip stock passes, 55 means for rotating at least one of the rolls to move the stock between them with the opposed surface of the rollers being shaped to flow the metal of the strip stock to give the same a curvature, and means for positioning a core adjacent the rollers where the strip stock emerges from the rolls so that the strip stock winds itself upon said core.

In testimony whereof I affix my signature.
HARRY W. BUNDY.
